UNITED STATES PATENT OFFICE.

HENRY S. FERGUSON, OF OKMULGEE, OKLAHOMA.

SLIDING-DOOR LOCK.

1,201,708.

Specification of Letters Patent. Patented Oct. 17, 1916.

Application filed January 29, 1916. Serial No. 75,158.

To all whom it may concern:

Be it known that I, HENRY S. FERGUSON, a citizen of the United States, residing at Okmulgee, in the county of Okmulgee and 5 State of Oklahoma, have invented new and useful Improvements in Sliding-Door Locks, of which the following is a specification.

This invention relates to improvements in sliding door locks and has particular application to a lock for sliding doors of freight 10 cars and the like.

In carrying out the present invention, it is my purpose to provide a sliding door lock whereby the door may be effectively locked 15 in closed position and the lock sealed and wherein the locking bolt will be under the control of a magnetic key so that opening of the door, in the event of the unauthorized breaking of the seal, by a key other than a 20 magnetic key will be prevented.

It is also my purpose to provide a sliding door lock wherein the component parts will be so arranged and correlated as to reduce the possibility of derangement to a minimum 25 and enable access to be had to such parts for the purposes of cleaning and repairing.

With the above and other objects in view, the invention consists in the construction, combination and arrangement of parts hereinafter set forth in and falling within the 30 scope of the claims.

In the accompanying drawings; Figure 1 is a view in side elevation of a lock constructed in accordance with the present invention, the same being shown in use. Fig. 2 is a horizontal sectional view therethrough. Fig. 3 is a vertical sectional view through the same. Figs. 4, 5 and 6 are views of details of the invention.

40 Referring now to the drawings in detail, 1 designates a portion of a sliding door. Mounted upon the outer side of the door 1 adjacent to the front edge thereof is a vertical block 2, while mounted upon the inner 45 surface of the door adjacent to the front edge thereof and disposed immediately behind the block 2 is a block 3 and passed through alining openings in the blocks 2 and 3 and in the door 1 are securing bolts 4 50 acting to hold the blocks securely fastened to the door. The inner block 3 is formed with a transverse slot 5 disposed at a point between the ends of the block and passed through alining openings formed in the 55 blocks 2 and 3 and the door is a rod 6 extending through the slot 5 and having the

outer end thereof provided with a handle 7 whereby the rod may be rotated.

8 designates a locking bolt having one end disposed within the slot 5 and the other end 60 projecting beyond the forward edge of the door. The end of the bolt 8 within the slot 5 is pivoted upon the rod 6 and this bolt is formed with a longitudinally extending vertical slot 9 and disposed within the slot 65 9 is a lever 10 having one end fixed upon the bolt 8 and the other end formed with a hook 11. The lower edge of the bolt 8 at the outer end thereof is formed with a groove 12 that opens into the slot 9 and 70 formed at the juncture of the groove 12 with the slot 9 is a shoulder 13 disposed adjacent to the hook 11 on the lever 10. The jamb of the door opening is formed with a recess 14 in alinement with the bolt 8 and 75 fastened within this recess 14 is a substantially rectangular casing 15 having the front and rear ends open and secured to the lower wall of the casing 15 and disposed within such casing is a block 16 having the upper 80 edge formed with a shoulder 17 adjacent to the front end of the block and with a shoulder 18 adjacent to the rear end of the block, while extending transversely of the casing 15 and secured to the opposite side walls 85 thereof adjacent to the top wall is a pin 19 upon which is mounted for swinging movement a holding lug 20. In the present instance, a vertical block 21 is fastened to the outer side of the door jamb and is formed 90 with an opening 22 alining with openings in the door jamb and in the front wall of the casing 15 and passed through these alining openings is a rod 23 having the inner end formed with a laterally projecting lug 95 24 arranged adjacent to the shoulder 17 and disposed alongside of the block 16, while fastened to the outer end of the rod 23 is a handle 25.

In practice, when the door is slid to closed 100 position, the bolt 8 carrying the lever 10 passes through the casing 15, while the shoulder 13 drops over the shoulder 18 on the block 16 and the hook 11 on the lever 10 engages behind the shoulder 17 on the block 16 and the holding lug 20 engages the upper 105 edge of the lever 10 to hold the latter against upward swinging movement under the action of the rod 6. Thus, the door is securely held in locked position. The front portion of 110 the door jamb is formed with a keyhole 26 in juxtaposition to the holding lug 20 and a

magnetic key 27 is adapted to be inserted through the keyhole 26 and when such key is passed through the keyhole, it attracts the holding lug 20 with the effect to swing such 5 lug away from the upper edge of the lever 10, thereby permitting the latter to be swung upwardly under the action of the rod 6 and handle 7 to disengage the hook 11 from the shoulder 17. To completely unlock the door, 10 the rod 23 is rotated under the action of the handle 25 and in the rotation of the rod 23, the lateral lug 24 engages the lower edge of the locking bolt 8 and swings the latter upwardly to disengage the shoulder 13 from 15 the shoulder 18, thereby permitting the door to be slid to open position.

In the present instance, the outer surface of the vertical block 21 at a point above the rod 23 is formed with a transverse slot 28 20 and mounted within the slot 28 and capable of swinging movement therein is a horizontal bar 29 having one end formed with an inwardly projecting lug 30 adapted to overlap the keyhole 26, and the remaining end 25 designed to enter the recess 31 formed in the block 2 on the outer side of the door 1 and pivoted within said recess. Formed in the outer surface of the strip 29 is a vertical slot 32 designed to aline with a similar slot 33 30 formed in the handle 25 on the outer end of the rod 23. Passed through alining openings in the block 21 and the door jamb above the strip 29 and suitably secured in such 35 openings is a rod 34 having the outer end formed with a lug 35. This lug 35 is provided with a slot 36 that alines with the slots 32 and 33 and slidably mounted within the slot 36 is a sealing pin 37 formed with a longitudinally extending slot 38 that receives a pin 39 extending across the slot 36 40 in the lug 35, the pin and slot 39 and 38 co-acting to prevent detachment of the sealing pin from the lug 35. After the door is locked in closed position, as previously 45 described, the bar 29 is swung within the slot 28 to engage one end thereof in the recess

31 and move the lug 30 over the keyhole and in this position of the strip, the vertical slot in the outer surface thereof alines with the slots in the lug 35 and the handle 25 so that 50 the sealing pin 37 may be passed through such alining slots and a seal applied to the lower end thereof to seal the door in locked position.

While I have herein shown and described 55 the preferred form of my invention by way of illustration, I wish it to be understood that I do not limit or confine myself to the precise details of construction herein described and delineated, as modification and 60 variation may be made within the scope of the claims and without departing from the spirit of the invention.

I claim:

1. In a sliding door lock, a bolt mounted 65 upon the door and projecting over one edge thereof and formed with a longitudinally extending slot, a lever pivoted within said slot and formed with a hook, keepers carried by the door jamb and adapted to be engaged by said bolt and hooked lever respectively, and means for moving said bolt and lever out of engagement with the respective keepers.

2. In a sliding door lock, a bolt mounted 75 upon the door and projecting over one edge thereof and formed with a longitudinally extending slot, a lever pivoted within said slot and formed with a hook, keepers carried by the door jamb and adapted to be 80 engaged by said bolt and hooked lever respectively, means for moving said bolt and lever out of engagement with the respective keepers, and means for sealing the door in closed position succeeding the locking 85 thereof.

In testimony whereof I affix my signature in presence of two witnesses.

HENRY S. FERGUSON.

Witnesses.
